BOOK HANGER

Paine L. Bush, Dallas, Tex.

Application April 28, 1933, Serial No. 668,407

5 Claims. (Cl. 129—38)

This invention relates to new and useful improvements in book hangers.

One object of the invention is to provide a hanger for books such as telephone directories or other reference books whereby such books may be conveniently suspended in readily accessible locations without the necessity of marring furniture or fixtures by supporting nails or hooks.

Another object of the invention is to provide a book hanger which is of unique shape and capable of peculiar mannerisms in use and has prominent portions thereof adaptable to advertising displays thus making an attractive and distinctive advertising medium.

A further object of the invention is to provide an article of manufacture having great utility as a book hanger as well as an advertising medium and which may be readily and easily adapted to a book for use without injury to the same, and which is of simple construction and efficient manufacture, whereby the same may be produced at an extremely low cost thereby increasing the sales possibilities and making for large volume output.

A construction designed to carry out the invention will be hereinafter described together with other features of the invention.

The invention will be more readily understood from a reading of the following specifications and by reference to the accompanying drawings in which an example of the invention is shown, and wherein:

Figure 1 is a side view of a device constructed in accordance with the invention,

Figure 2 is a top view of the same,

Figure 3 is a partial top view showing the clamp in a closed position,

Figure 4 is a perspective view showing the device in use for suspending a book at the side of a desk,

Figure 5 is a view taken at right angles to Figure 4,

Figures 6 and 7 are detailed views showing how advertising displays may be mounted on the device for prominent exhibition,

Figure 8 is a partial perspective view of a modified form of the invention, and

Figure 9 is a partial perspective view showing another modification of the invention.

In the drawing the numeral 10 designates a piece of iron wire, or other material suitable for the purpose, which is bent to form a V shaped clamp A. The extremity of one stem 11 of said clamp is turned inwardly to form a curved lip

11' for engaging under a crook 12' at the extremity of the other stem 12 for closing the clamp, and is maintained in a closed position by the tension of the wire.

A curved neck 13 extends outwardly from the crook 12' in the same plane as the stems of said clamp and has hooks or claws 14 extending from its outer end on opposite sides of said plane. These hooks are turned inwardly toward the clamp A so that their ends will form suspension points from which the clamp and objects held thereby will hang. Rubber sleeves 14' cover the ends of the hooks to provide a positive gripping surface without danger of marring furniture or other objects with which they come in contact.

It will be noted that this device is formed from a single piece of wire with the hooks 14, as shown in Figures 1, 2, 4, 5 and 6, having a diamond like shape for supporting an advertising display 15 of similar shape. This display is mounted by means of wing projections 15' which are clamped about the wire. Such displays may, of course, be of various sizes and shapes and likewise attached in various ways without detracting from the invention. An elongated advertising display 16 may also be secured to the stem 12 of the clamp such as by crimping the corners 16' of said display about said stem. This display should correspond in size with the binding edge of the book to which the hanger is to be attached. It is preferable that these displays be made of durable material such as sheet metal so as not to be easily destroyed.

In use, with the clamp A in an open position, the stem 11 is inserted between the center pages of a book B with the stem 12 extending longitudinally of the binding edge of said book. The clamp is then closed by engaging the lip 11' with the crook 12' whereby the device is ready for use. It will be noted that the book is not marred or injured by application of the clamp thereto.

As best shown in Figures 4 and 5 the projecting ends of the hooks readily permit the book to be suspended from all manner of objects as only a minute space is required for support of either of said hooks. The device was conceived and is most adaptable for suspension of a book such as a telephone directory, rate manual or other largely used reference books, from a horizontal plane surface such as alongside a desk or table with the advertising displays attached thereto in prominent view. Obviously such an article has

great utility both as a book hanger and as an advertising medium.

In Figure 8 I have shown a modified form of the invention wherein the stem 12 is straight and 5 is engaged by a crook 17 projecting at right angles from the extremity of the other stem 11 for closing said clamp. Hooks 18 similar to the hooks 14 are formed at the extremity of the stem 12, thereby eliminating the curved neck 13. In 10 this form it has been found desirable to make the hooks slightly longer than those in the form having the curved neck 13.

In Figure 9 I have illustrated another modification of the invention wherein a curved neck 19, 15 similar to the neck 13, extends from the extremity of the stem 12 and is provided with an elongated straight portion 20 the outer end 21 of which is turned inwardly toward the clamp and shaped to form the projecting hooks 18, hereinbefore referred to. This form permits the mounting of an advertising display 22 along the straight and end portions 20 and 21 in a vertical position for exhibition of both sides of said display.

It is pointed out that the hooks 14 act as pivots 25 from which the book will swing during its tendency to balance when suspended after use thus attracting attention by reason of such movements to the hanger and likewise to the displays.

It is obvious that the device may be produced 30 at a very small cost, consequently increasing the sales possibilities and making for large volume manufacture.

Various changes in the size and shape of the 35 different parts, as well as modifications and alterations, may be made within the scope of the appended claims.

What I claim is:

1. In a new article of manufacture, a book hanger; a clamp for holding a book longitudinally of its binding edge; a curved neck integral with and extending from the clamp; said neck having hooks extending outwardly therefrom on opposite sides of the plane common to the neck and the clamp; the hooks having their ends turned toward the clamp.
- 45 2. In a book-hanger, a clamp comprising a

pair of members adapted for gripping a book therebetween, said clamp having a substantially large hook extending upwardly and outwardly from one end of said clamp in a plane common to the gripping members of the clamp, and claws extending from opposite sides of the end of said hook at substantially right angles to said plane, the outer ends of said claws being shaped to form points of suspension for said clamp and the book held thereby, said claws having their outer ends rounded and enclosed in friction tips.

3. A new article of manufacture, a book-hanger comprising a wire shaped in the form of a clamp consisting of two stem-like members, one of the stems being adapted for extending between the leaves of a book with the binding edge of said book confined longitudinally between the stem-like members, the stems being joined at one end by a connecting bend for supporting the lower end of the binding edge of the book, the upper end of one stem being bent to form a hook for engaging the other stem outside the upper edge of said book, the other stem-like member being elongated and formed beyond the point of engagement with the other stem in a suspension hook extending outwardly from the clamp in a plane to both stems, the end of the suspension hook being shaped to form projecting claws overhanging opposite sides of the clamp, the ends of the projecting claws being rounded and curved toward the clamp to form pivotal suspension points.

4. In a book hanger, a clamp having a resilient hook-like member extending outwardly therefrom, said resilient member having opposite laterally projecting claws at its outer end, the ends of said claws being shaped to form pivotal points of suspension for the clamp.

5. In a book hanger, a clamp comprising a pair of stem-like members having their lower ends connected and their upper ends shaped for engagement with each other, one of said stems being elongated and having its end portion shaped to form laterally projecting claws having their ends curved toward the clamp.

PAIN L. BUSH.
